UNITED STATES PATENT OFFICE.

FRANK J. THULL, OF MINNEAPOLIS, MINNESOTA.

TWINE-CUTTER.

1,087,471.

specification of Letters Patent. Patented Feb. 17, 1914.

Application filed May 11, 1912. Serial No. 696,714.

To all whom it may concern:

Be it known that I, FRANK J. THULL, of Minneapolis, Hennepin county, Minnesota, have invented certain new and useful Improvements in Twine-Cutters, of which the following is a specification.

My invention relates to twine or thread cutters and is designed particularly for use in connection with bag sewing machines.

10 The object of my invention is to provide a twine cutter which may be located close to the stitching mechanism to enable the operator of the machine to easily and quickly cut the twine when the bag has been sewed.

15 A further object is to provide a twine cutting device of simple construction and one which can be easily and quickly applied to the machine.

20 My invention consists generally in various constructions and combinations, all as hereinafter described and particularly pointed out in the claims.

25 In the accompanying drawings forming part of this specification, Figure 1 is a side view, partially in section, of a portion of a bag sewing machine with my invention applied thereto, Fig. 2 is a detail view of the twine cutting knife, showing the movable and stationary jaws; Fig. 3 is a similar 30 view, looking at the other side of the knife, Fig. 4 is a top view, partially in section, illustrating the means for securing the device to the machine frame.

35 In the drawing, 2 represents the frame of the machine having a downwardly extending arm or bracket 3 in which the stitching mechanism, which I have not thought necessary to illustrate in detail herein, is mounted. 4 is a hanger, between 40 which and the lower portion of the arm 3 the folded end of the sack 5 is fed. During this feeding operation the open end of the sack is stitched and closed.

45 Twine cutting devices of various kinds have been provided, but all of them have proved more or less unsatisfactory on account of their number of parts, the time required for adjustment and the location of the knife, which frequently is located a considerable distance from the stitching mechanism where it cannot be conveniently reached by the operator.

50 6 is a block secured to the hanger 4 by screws 7 or other suitable means, and having a hole 8 near one end and a slot 9 com-

municating with said hole, forming jaws 10 which are clamped on a screw 11 by means of a clamping screw 12.

13 is a stationary plate mounted on the block 6 by any suitable means, preferably 60 pins 14, and provided at one end with a V-shaped recess forming stationary jaws 15 having cutting edges 16. 17 is an L-shaped plate having cutting edges 18 at one end and pivoted at the intersection of its arms 65 on the screw 11. The plate 17 is adapted to bear on the plate 13 and the cutting edges 18 converge toward one another and sweep across the V-shaped opening in the stationary plate coöperating with the cutting edges 70 thereof to sever the twine or cord inserted between them. By loosening the clamping screw 12 the screw 11 may be withdrawn and the plate 17 adjusted toward or from the stationary plate 13. When the desired ad- 75 justment of the screw 11 is obtained the clamping screw 12 is tightened to clamp the jaws 10 on the screw 11 and prevent it from becoming accidentally loosened.

75 The plate 17 oscillates continuously with 80 the movement of the machine and for the purpose of operating it I provide a pitman-rod 19 attached at 20 to one arm of the plate 17 and reciprocated by an eccentric 21 on a shaft 22. The reciprocation of the 85 rod 19 will swing the plate 17 and its cutting edges past the stationary cutting edges of the plate 13 and the location of the cutting edges close to the stitched portion of the sack will enable the operator, as soon as 90 the stitching operation is completed, to slip the thread between the jaws where it will be easily and quickly severed by the movement of the plate 17.

95 It will be noted in Figs. 2 and 3 that the cutting edges of the stationary and movable knives converge in opposite directions so that when a thread or twine is inserted between the knives a drawing or shearing cut will be obtained and the twine will be instantaneously and completely severed.

100 I claim as my invention:—

1. A thread cutting device comprising a block having a socket therein, a screw fitting within said socket, said block having 105 clamping jaws to grip said screw, a stationary knife mounted on said block and provided with cutting edges, a movable knife mounted on said screw and having cutting edges adapted to sweep past the 110

cutting edges of said stationary knife and means for operating said movable knife.

2. In a bag sewing machine, the combination, with a stitching mechanism, of a stationary knife mounted adjacent to said mechanism and having a V-shaped recess therein provided with cutting edges, a movable knife having tapered cutting edges adapted to swing past the cutting edges of said stationary knife, a shaft, an eccentric thereon, and a pitman-rod connecting said eccentric with said movable knife.

3. The combination, with a stitching machine having a vertically arranged hanger, of a stationary knife secured horizontally to the lower portion of said hanger and provided with a cutting edge, a pivoted knife also supported by said hanger in a substantially horizontal position and having a cutting edge adapted to sweep by the cutting edge of said stationary knife, a horizontal shaft in the rear of said hanger, an eccentric thereon, and a pitman extending forward horizontally from said eccentric and

connected with said pivoted knife to move 25 the same in a substantially vertical plane.

4. The combination, with a stitching machine, of a block secured thereon, a plate mounted on said block and provided with cutting edges and forming a stationary 30 knife, an oscillating knife having cutting edges adapted to sweep by the cutting edges of said stationary knife, a screw passing through said oscillating knife and said plate and into a socket in said block and 35 clamping jaws to grip said screw, and a clamping screw for said jaws, the loosening of said clamping screw allowing the adjustment of said screw and the movement of said oscillating knife toward or from said 40 stationary knife, and means for operating said oscillating knife.

In witness whereof, I have hereunto set my hand this 7th day of May, 1912.

FRANK J. THULL.
